EDWARD F. BURKE, OF SIOUX CITY, IOWA, ASSIGNOR OF ONE-FOURTH TO JOHN M. LICHTY, OF SIOUX CITY, IOWA.

WRECKING-TOOL.

1,389,183.

Specification of Letters Patent. Patented Aug. 30, 1921.

Application filed July 20, 1920. Serial No. 397,652.

To all whom it may concern:

Be it known that I, EDWARD F. BURKE, a citizen of the United States, residing at Sioux City, in the county of Woodbury and State of 5 Iowa, have invented a new and useful Wrecking-Tool, of which the following is a specification.

This invention relates to implements for wrecking frame structures of all descriptions 10 such as buildings, fences, bridges and culverts.

Objects of the invention are to provide a tool of relatively simple construction, which is easy to operate, which will save material 15 without breaking or otherwise marring it, which will remove all sizes of lumber with ease and will pull boards or the like on both sides of a joist.

A further object is to provide a wrecker 20 which is quick-acting, the parts automatically returning to their original position after each drawing of the boards.

The invention will be best understood from a consideration of the following detailed description taken in connection with the accompanying drawing forming part of this specification, with the understanding, however, that the invention is not confined to any strict conformity with the showing in the 25 drawing, but may be changed and modified so long as such changes and modifications mark no material departure from the salient features of the invention as expressed in the appended claims.

35 In the drawing:

Figure 1 is a perspective view of the improved tool in working position, showing a portion of a building in dotted lines with one of the boards about to be drawn from 40 a joist.

Fig. 2 is a top plan view of the frame or base of the implement.

Fig. 3 is a front elevation of the tool with parts in vertical cross section.

45 Fig. 4 is a side elevation of one of the hooks shown removed from the tool.

Fig. 5 is a side elevation of the lever arm shown by itself.

The numeral 10 designates the base or 50 frame proper of the present implement, which comprises a flat plate having one end cut away as at 11 to save material and reduce the weight of the tool. A pair of hollow sleeves 12 are joined to the upper face of the frame 10 and extend outwardly from the end

which has the cut-away portion 11 in parallel relation to each other. The length of these sleeves 12 is such that they terminate at a point intermediate the ends of the plate. A pair of plates 13 rise from the frame on the 60 same side as the sleeves 12, these plates being parallel to each other and spaced apart and extending at right angles to the base, and a flange 14 is provided on the end of the frame remote from the sleeves 12. The width of 65 the flange 14 is less than the width of the frame, and the flange is disposed intermediate the side edges of the frame, extending at right angles thereto. The plates 13 preferably are joined with the flange 14 to give 70 greater rigidity to the structure, with the flange 14 at right angles to the two plates. Preferably, the plates 13, the flange 14 and the sleeves 12 are all cast integrally with the frame 10, though these parts may be formed 75 separately and secured to the frame in any desirable way.

A pair of hooks 15 is employed on the present tool. These hooks each comprise a straight shank or portion formed from a flat 80 bar and a return bend portion 17 parallel to the straight portion and lying in the plane thereof. The return bend portion 17 should have a length at least equal to half the length of the straight portion of the hook. The 85 hooks have heads 16 at their bases and there are joined with rods 18 extending at right angles to the straight shanks of the hooks. The rods 18 are round in cross section and may be integral with the hooks or removably 90 secured thereto in any desirable way. The rods 18 each pass through a sleeve 12 and are slidable therein, being held spaced from the upper face of the frame 10 a short distance. A coil spring 19 is mounted on each rod 18 95 to press between the head 16 and the inner end of the corresponding sleeve 12. The outer end of each rod 18 is bored transversely whereby a cotter pin 20 or similar element may be passed through the rod to prevent 100 the spring 19 from moving the rod 18 out of the sleeve 12.

The normal position of the hooks is that illustrated in Fig. 1, where the straight portions of the two hooks lie substantially in the plane of the flange 14 of the base, being parallel to each other at right angles to the base. In this position, the return bend 17 of the two hooks will lie wholly outside of the base 105 in position to engage with the board. 110

- The two hooks are maintained parallel to each other by means now to be described. Each hook has a hole 21 provided at an intermediate point along the straight portion thereof and adapted to receive a bolt 22 passing through the two hooks. A tubular member 23 surrounds the bolt 22 and has its ends abutting against the inner faces of the hooks. A pair of spacing sleeves 24 are mounted on the tubular member 23, and the end of an operating lever is connected to the two hooks by being mounted upon the tubular member 23 between the two spacers 24.
- 15 The lever arm comprises a long arm 25 and a short arm 27, and has a bore 26 for receiving a pivotal element 30 passed through the ears 29 of plates 13. The free end of arm 25 is fashioned into a handle, as shown, while the free end of arm 27 has an elongated arcuate slot 28. The tubular member 23 is passed through this slot 28 while the spacers 24 are of such diameter as to be maintained wholly without the slot during 25 the swinging of the lever arm.
- As indicated in Fig. 1, when it is desired to remove a plank or board from a frame structure, the hooks are placed with the return bend 17 on the inside of the board and 30 the bent section of the hooks fitting over the top or side edge of the board. The flange 14 will then rest against an adjacent board and the base or frame at the end thereof bearing the flange will also rest against that board, 35 which will provide a base or support. Then the lever arm 25 will be swung downwardly, which will cause the two hooks to reciprocate relatively to the base, compressing the springs 19 and effectively drawing the most stubborn board without injuring the same. As soon as the board is drawn, the two coil 40 springs will return the hooks to their original position, whereupon the implement will be ready for a second operation. If two 45 boards are joined to a single joist at their ends, it will be seen that the present implement will loosen both ends of the two boards at a single pull. The implement is so designed that it operates with a minimum of 50 exertion so that a boy of twelve may take off boards with ease and yet save the material.
- What is claimed is:—
1. In a wrecking tool, a base or frame, a lever pivotally mounted on the frame, a pulling hook slidably mounted on the frame, means imparting to the hook a normal tendency to remain in a position at one end of the frame and projecting beyond said end 60 whereby the hook may engage over a board without displacement from its normal position, and means connecting the hook and lever whereby swinging the lever slides the hook toward the other end of the frame.
  - 65 2. In a wrecking tool, a base or frame, a plurality of parallel sleeves provided on the frame, a plurality of rods slidable within the sleeves, a coil spring mounted on each rod, a hook secured to one end of each rod with the spring between the hook and the inner end of the sleeve, and means for causing travel of the hooks along the frame against the resistance of the springs.
  3. In a wrecking tool, a base or frame, a plurality of parallel sleeves provided on the frame, a plurality of rods slidable within the sleeves, a coil spring mounted on each rod, a hook secured to one end of each rod with the spring between the hook and the inner end of the sleeve, and a lever pivotally 75 mounted on the frame and connected with all the hooks whereby swinging of the lever in one direction pulls the hooks toward the sleeves against the resistance of the springs.
  4. In a wrecking tool, a base or frame, a flange upstanding from one end of the frame, a hook including a straight portion and a return bend portion substantially parallel to the straight portion slidably mounted on the frame, a spring holding the hook normally 80 in such position that its straight portion is substantially parallel to the flange with the return bend located beyond the end of the frame, and means for moving the hook inwardly with respect to the frame.
  5. In a wrecking tool, a base or frame comprising a flat plate, a pair of spaced ears rising from one face of the plate, a flange upstanding from one end of the plate, a pair of hollow sleeves provided on the same face 90 of the plate as the ears and end flange, said sleeves projecting beyond the end of the plate remote from said flange and being parallel to each other but terminating intermediate the ends of the plate, a lever pivoted between the ears, a pair of hooks connected to the lever whereby swinging of the lever slides the hooks along the aforementioned face of the plate, and a pair of rods connected rigidly to the ends of the hooks adjacent 95 the plate and slidable within said sleeves.
  6. In a wrecking tool, a base or frame comprising a flat plate, a pair of spaced ears rising from one face of the plate, a flange upstanding from one end of the plate, a pair 100 of hollow sleeves provided on the same face of the plate as the ears and end flange, said sleeves projecting beyond the end of the plate remote from said flange and being parallel to each other but terminating intermediate the ends of the plate, a lever pivoted between the ears, a pair of hooks connected to the lever whereby swinging of the lever slides the hooks along the aforementioned face of the plate, and a pair of rods connected rigidly to the ends of the hooks adjacent 105 the plate and slidable within said sleeves.
  7. In a wrecking tool, a base or frame comprising a flat plate, a pair of spaced ears rising from one face of the plate, a flange upstanding from one end of the plate, a pair 110 of hollow sleeves provided on the same face of the plate as the ears and end flange, said sleeves projecting beyond the end of the plate remote from said flange and being parallel to each other but terminating intermediate the ends of the plate, a lever pivoted between the ears, a pair of hooks connected to the lever whereby swinging of the lever slides the hooks along the aforementioned face of the plate, and a pair of rods connected rigidly to the ends of the hooks adjacent 115 the plate and slidable within said sleeves.
  8. In a wrecking tool, a base or frame comprising a flat plate, a pair of spaced ears rising from one face of the plate, a flange upstanding from one end of the plate, a pair 120 of hollow sleeves provided on the same face of the plate as the ears and end flange, said sleeves projecting beyond the end of the plate remote from said flange and being parallel to each other but terminating intermediate the ends of the plate, a lever pivoted between the ears, a pair of hooks connected to the lever whereby swinging of the lever slides the hooks along the aforementioned face of the plate, a pair of rods connected rigidly to the ends of the hooks adjacent 125 the plate and slidable within said sleeves, means to prevent sliding of said rods out of said sleeves and to prevent movement of the hooks along the frame beyond the end 130

having the flange, and means to maintain the hooks normally at said frame end.

7. In a wrecking tool, a frame, a lever pivotally mounted on the frame, a pair of hooks carried by the frame, means connecting said hooks and the lever comprising a bolt joined to both hooks, a tubular member mounted on the bolt between the hooks, a pair of spacing elements mounted on the tubular member one between either side of the lever and the corresponding hook, said lever having an arcuate slot in one end, said slot receiving the tubular member with the spacing sleeves acting as guides when the lever is 10 swung, and guiding means for the hooks provided on the frame.

8. In a wrecking tool, a frame, a pair of pulling hooks at one end of the frame,

spring-actuated means for connecting the hooks to said frame, and a lever pivoted to 20 the frame and connected to the hooks, whereby swinging of the lever actuates the hooks simultaneously toward the frame.

9. In a wrecking tool, a frame, guiding means thereon, a pair of pulling hooks located at one end of the frame, and movable in said guiding means, a lever pivoted on the frame and having a long and a short arm, the short arm being connected to the pulling hooks, and resilient means for sliding the hooks along the frame. 25 30

In testimony, that I claim the foregoing as my own, I have hereto affixed my signature.

EDWARD F. BURKE.
